UNITED STATES PATENT OFFICE.

EVERARD RICHARD CALTHROP, OF LONDON, ENGLAND.

PARACHUTE.

1,246,874.

Specification of Letters Patent. Patented Nov. 20, 1917.

Application filed October 18, 1915. Serial No. 56,635.

To all whom it may concern:

Be it known that I, EVERARD RICHARD CALTHROP, a subject of the King of Great Britain, residing at London, in the county 5 of Middlesex, England, have invented new and useful Improvements in and Relating to Parachutes, of which the following is a specification.

My invention has reference to parachutes 10 more particularly such as are intended for use with military or naval air craft where economy of space and the dispensing with all unnecessary weight are matters of the greatest importance.

15 Among the many reasons which have heretofore precluded the employment of ordinary parachutes on air craft for life saving purposes is the danger of the parachute failing to open; the very considerable fall 20 which must be allowed for before the parachute can commence to open or in other words to allow sufficient margin of fall to meet the uncertainties of opening; and the great amount of space occupied for it will 25 be obvious that if held in such a position as to be instantly available the resistance to the wind will be excessive and flogging and entanglement of the cords in an air current will result.

30 In the use of the ordinary parachute the apex of the cover is held by a releasing device attached to the cordage of the gas bag of the balloon. The cover and cords of the 35 parachute hang down and the sling for the aviator is attached to the car. When the descent is to be made the passenger carefully lowers himself into the sling and after seating himself and seeing that all is right pulls a cord which releases the attachment over 40 head and the parachute and its passenger falls.

Held in this manner by the apex the pull 45 of the weight of the aviator transmitted through the cords gathers the cover of the 50 parachute together into a compact mass and when it drops the gussets of the cover are necessarily all in close contact with each other.

It is usual to provide parachutes with a 55 hole through the top of the cover with a view to preventing or at least minimizing oscillation during descent and it will be apparent that as the parachute falls the rush and fraction of the air past the hole in the top produces a sensible vacuum within 60 the cover of the parachute with a tendency

to suck the gussets together throughout their whole length. In all cases there is a struggle 65 between the vacuum with its closing action at the top and the endeavor of the air to open the mouth of the parachute at the bottom and when it happens that the frillings of the gussets at the mouth of the 70 parachute are sucked together by the internal vacuum or are all closed by external air pressure the parachute fails to open and the aviator falls to his death.

While the actual launching of a parachute from a free balloon is a comparatively easy 75 matter as the balloon travels at the same speed as the air current and relatively to the balloon the air is completely undisturbed the same conditions do not obtain in the case of a captive balloon airship or aeroplane. Except on the occasion of a dead calm in the 80 case of a captive balloon and the very rare coincidence of a momentary synchronization of the speed of an airship or aeroplane with the speed of an air current when traveling in the same direction any attempt to 85 launch an ordinary parachute results in its being dragged through the air and then all kinds of difficulties and dangers are liable to arise. The main damage and difficulty which has altogether precluded the use of 90 parachutes in such circumstances is the flogging together and hopeless entanglement of the 95 parachute cords.

Now the objects of my present invention are to provide a parachute which may be instantly launched with a passenger from any description of air craft with the absolute certainty of rapid and positive opening in all circumstances; to provide means whereby the risk of any part of the rigging becoming 100 entangled or fouled is entirely eliminated and to provide a parachute which with its associated parts may be normally contained in a small space, present small resistance to the air and at the same time be instantly available for use in an emergency without any preparation and to provide means whereby the operations of launching and opening shall take place automatically immediately the weight of the aviator is exerted upon the sling of the 105 parachute.

With these and such other objects in view as may hereinafter appear or are incidental thereto my invention in its broadest aspect may be said to contemplate a construction 110 wherein means are provided for obtaining kinetic control of all the functions of the

parachute so that its parts shall act only in ordered sequence and in predetermined paths to the end of insuring absolute reliability of action in all circumstances.

5 More specifically considered my invention consists in the provision of means for supporting and retaining the parachute body in symmetric folds or plaits in such a manner that as the weight of the load is exerted 10 through the guy ropes upon the periphery said folds or plaits shall be successively released from the periphery toward the center.

Still more narrowly regarded my invention consists in the provision of a support 15 for the parachute body its guy ropes and trapeze sling or harness so disposed that the parachute body may be laid in symmetric folds or plaits on, within, or around said support, the arrangement being such that when 20 weight is exerted upon the trapeze sling or harness such weight shall first be taken up by the guy ropes and then transferred through them to the peripheral fold or plait of the parachute cover thereby freeing it 25 from its support the remaining folds from the periphery to the center being then successively freed from the support and the parachute and its load automatically released to allow it to descend with its load 30 safely to the ground.

It should be noted that wherever I refer for convenience to "guy ropes" I intend this expression to embrace "tapes" as I have found that flat tapes or webbing of suitable 35 material is preferable in practice as risk of twisting and tangling is positively prevented.

In order that my invention may be readily understood and carried into effect by those 40 skilled in the art to which it appertains I will now proceed to describe the same fully for which purpose reference is to be had to the accompanying drawings in which:

Figure 1 represents a section of a device 45 embodying my invention showing the parachute in position and ready for release.

Fig. 2 is a plan view of a part of the lower cover hereinafter more particularly referred to the left hand half of the figure illustrating 50 the arrangement of the tapes constituting the rigging of the parachute while the right hand portion shows the manner in which the cover is marked to facilitate the arrangement and fixing of said tape rigging in position thereon.

Fig. 3 is a detail view of the means employed for connecting the tape rigging with the parachute.

Figs. 4 to 13 are diagrams illustrating the 60 action of the parachute in use.

Referring now to Fig. 1 A indicates an annular frame to which is positively secured a disk B which in the construction here shown is in the form of an obtuse angled 65 cone. The frame A is formed with a de-

pending conical flange C and also has secured to it a handle D whereby the device as a whole may be slung from an air craft in the desired position either centrally by the aperture a or from two points b, c to 70 prevent swiveling.

The device so far described comprises therefore the central annular frame A and the disk B which combined form what for convenience in description I will term the 75 "launching disk" as it is from this disk that the parachute is launched by the weight of its passenger as will hereinafter appear.

The annular frame A is provided with an inwardly projecting flange E adapted to be 80 engaged by the rubber washers F and G carried by the bolt H whereby the member I to which the sling trapeze or aviators harness of the parachute is attached may be detachably connected with said launching 85 disk. The bolt H also supports the main tape retaining member or center piece J to which the main tapes K—which form the equivalent of the usual guy ropes—are positively secured by means of the hook bolts L 90 adapted to engage the buckle loops or equivalent members M carried by each of the aforesaid main tapes K. Clamped to the top of the disk B by means of the annular frame A is a cover N of appropriate water- 95 proof material provided with an annular flap O at the periphery the edge of the cover N and said flap O forming a housing between which is located the edge of the lower waterproof cover P which is clamped to the 100 center bolt H. These covers are provided with rubber rings R at the edges and serve when in the position shown in Fig. 1 to completely inclose and protect the parachute and its rigging and the launching disk. 105

The lower cover P also performs a further and extremely important function namely to support and retain the rigging tapes arranged in packs as will presently be explained in proper spaced relation without 110 risk of entanglement and in such a manner that they shall act only in ordered sequence and in predetermined manner.

The various operations of packing and preparing the parachute for launching will 115 now be explained: The parachute body S is as is usual in most parachutes provided with an aperture in the center or apex in order that the stream of compressed air passing through it may act as a universal rudder to prevent oscillation of the parachute body and this aperture is utilized in my invention as a means of connecting the apex of the parachute with the launching disk. For this purpose said aperture is edged with a 120 rubber cord or ring T which is passed over the flange C thereby detachably securing said parachute thereto. The parachute body S is now laid along the underside of the disk B and over its edge as indicated by the 125

broken lines in Fig. 1 and after being radially plaited is laid in concentric folds on the upper surface of the launching disk each fold being temporarily secured in place 5 by tying a thread U around it. When the whole of the body is thus stowed on the launching disk the periphery thereof is brought over the edge of the launching disk with the eyelets V in position for the attachment of the tapes constituting the rigging 10 the particular construction and disposition of which is a feature of the greatest importance and will therefore now be described in detail.

15 It will be seen on reference to Fig. 13 that the rigging of the parachute comprises the main tapes K and the forked tapes W serving to connect said main tapes K with the parachute body S and which for convenience of description I will term the "doublet tapes". Both the main and the doublet tapes are made into packs and the manner in which this is effected will be seen by referring to Fig. 2. The cover P with the 20 center bolt H , member J and washers F and G is supported preferably on a suitable frame in a convenient position and the tapes constituting the rigging arranged thereon in the following manner it being first 25 promised that in order to obviate any mistakes in the arrangement of said tapes the cover P is marked with numbered and colored divisions corresponding with the several tapes which are also numbered.

30 35 The right hand portion of Fig. 2 illustrates a portion of the cover P before the tapes are arranged thereon said cover being provided with numbered spaces upon which the numbered tapes are laid. One end of 40 each of the main tapes K is secured to the member J by means of the buckles M carried thereby being engaged with one of the hook bolts L the upturned edge of said member J being as shown in Fig. 2 provided with 45 recesses n in which the buckles M engage so retaining them securely in position.

50 Each main tape K is now laid in a plurality of laps one on the other to form a pack the opposite end of each tape terminating in a buckle Y to which its corresponding doublet tape is secured a stout rubber ring Z being passed around the pack thus formed so holding the laps together. In order to retain the pack of tape thus 55 formed upon the cover P and to prevent it shifting said cover is provided with buttons d and a light rubber band e is placed around the pack and engaged with the button d thereby holding said pack in position. 60 The doublet tapes W attached to the buckle Y are now also laid in laps one on the other to form a pack a suitable rubber ring f being employed to hold the laps together and said packs are retained in position upon the 65 cover P by the rubber bands e and buttons d .

Considering one main tape and one doublet tape as constituting a unit it will be observed that the terminals of the main tape pack lie in opposite directions while the terminals of the doublet tape pack are at 70 the same end of the pack. The apparently slight difference in the lapping of the tapes is however of the greatest importance and the reason of this arrangement will be fully explained when the operation of my improved device is hereinafter considered. 75

The parachute having as above stated been snugly stowed upon and supported by the launching disk the package thus constituted and contained within the upper cover N is 80 now placed upon the lower cover P on which the rigging tapes are arranged and fastened as described the rubber washers F and G engaging the flange E on the frame A thus detachably connecting the cover P and center piece with the frame A . The hook g carried by the doublet tapes W are now engaged with their respective eyelets V on the periphery of the parachute body each eyelet being preferably numbered to correspond with the numbered tapes. The connection between the doublet tapes and the 85 parachute body is preferably effected by the S shaped hook g having a rubber sleeve h which when the connection is made is 90 slipped over the hook as shown in dotted lines in Fig. 3 thereby effectually preventing the accidental disconnection of the hooks with the parachute or tapes. 95

All connections having been made in the 100 manner above described the flap O is turned back and the edge of the cover N pulled down over the edge of the launching disk then the edge of the lower cover P is pulled up over the edge of the cover N and the 105 cover P pulled down over the edge of the lower cover P the overlapping of the covers thus completely inclosing all the operative parts and making an airproof and water-proof joint. 110

The sling trapeze or harness for the passenger is now attached to the member I and the whole device suspended by the handle D in a convenient position from the airship or aeroplane ready for instant use. 115

The central aperture in the frame A is preferably normally covered by a cover i to prevent the admission or escape of air to or from the interior of the parachute body during its opening and I may utilize the 120 space inclosed by said cover as a receptacle for printed instructions for the use of the parachute and launching apparatus.

I will now describe the action of my improved parachute which in the diagrammatic view Fig. 5 is shown as being slung from an airship and the passenger about to jump therefrom. As the passenger seats himself in the sling or trapeze k his weight will first cause the rubber washers F G at 125 130

the top of the bolt H to be disengaged from the flange E of the frame A. Simultaneously the bottom cover P with its center piece will be detached and the main tape 5 packs K thrown into tension. Owing to the manner in which these tapes are lapped—namely with their terminals in opposite directions—the rubber rings Z cause the unlapping of the tapes K to be accompanied 10 by continuous friction and resistance which not only operates to retard to some extent the speed or fall of the passenger but keeps the tapes so taut that they do not touch one another notwithstanding their close proximity. A further and most important advantage of this arrangement is that all possibility of the tapes becoming entangled even when the parachute is being dragged against the fiercest gale is entirely obviated.

20 Fig. 6 illustrates the position of the parts at the moment the passenger throws himself from the airship and as he continues his fall the main tapes K become fully extended as shown in Fig. 7. Now it is necessary at this 25 juncture in the sequence of operations that the doublet tapes should all be thrown into tension simultaneously but not before the main tapes K are extended to their full length. To this end the buckles Y carried 30 by the end of the main tapes and to which the doublet tapes are also attached are connected by readily rupturable connections such as rubber bands l which in turn are connected by cords m to the flange C of the 35 frame A.

Now it will be seen that with this arrangement when the main tapes are fully extended the whole of the weight of the passenger will be exerted upon the rubber bands l 40 which will thereby be instantly snapped but the snapping is de-synchronized by the cords m being of different lengths and after the shock is thus modulated the weight becomes transferred to the pack of doublet 45 tapes. Said doublet tapes are as above stated so lapped that their terminals are at the same end of the pack an arrangement which produces a curiously different result to the method of packing the main tapes.

50 Immediately the terminals of the doublet tapes are put in tension the rubber ring f is frictionlessly thrown off and the whole pack instantly released as shown in Fig. 8. Subsequently the parts arrive at the position 55 shown in Fig. 9 and it will be observed that both the main and the doublet tapes are fully extended before any pull commences on the cover of the parachute which issuing from the launching disk with but 60 little friction presents hardly any resistance to the pull of the doublet tapes and if means were not provided for fully releasing the doublet tapes before the effort was exerted on the peripheral fold of the parachute there 65 would be considerable risk of a one-sided

pull being exerted which might give rise to dangerous contingencies. On the pull being exerted on the periphery of the parachute each fold is successively and in ordered sequence brought over the edge of the launching disk until the pull on the body is 70 exerted on the rubber ring T engaging the flange C which ring then expands allowing the center portion of the parachute body to slip away whereupon the last contact of the 75 parachute ceases which is thus completely launched containing within its body a cylindrical column of air of approximately the diameter of the launching disk and extended from the mouth to the apex as shown in 80 Fig. 11.

The automatic opening of the parachute will be understood by reference to Fig. 12 as it will be seen therefrom that by the 85 snatch of the fall of the passenger the entrapped and compressed cylindrical column of air is immediately converted into a bun shaped cushion extending laterally to the periphery and as this air cushion augmented by its increasing internal pressure due to 90 the fall of the parachute and the increase of the area of the opening of the mouth thereof extends laterally said parachute mouth is pushed out against the resistance of the tapes supporting the weight of the passenger. 95

As the pressure of air within the cover is from the commencement of the pull increasingly greater than that of the surrounding air absolute security in operating is at all 100 times insured.

To prevent unauthorized tampering with the parachute and its rigging assembled in the manner hereinbefore described and to insure that an aviator shall have a guarantee that the device has not been interfered with I contemplate the employment of suitable means for sealing the upper cover N and lower cover P together such as by providing said covers with tabs adapted to 105 be connected by an easily ruptured connection and an appropriate seal. The nut carried at the head of the bolt H may also be appropriately sealed for a like purpose.

In the foregoing description I have particularized the construction of a parachute launching device which from numerous trials under actual working conditions has been found to operate with great precision and certainty in all circumstances but various modifications may be made without 115 in any way departing from the principle of the invention.

While I have as above stated described in the foregoing specification the construction 120 of parts and operations preferred it is to be understood that numerous changes of construction and operation may be made without departing from the spirit and scope of the invention and I therefore do not wish 125 130

to be understood as limiting the scope of my claims by the positive terms employed in connection with the description.

What I claim is:

- 5 1. In a parachute, the combination with a parachute body radially plaited and laid in concentric folds, of a launching disk for supporting said body in said symmetrical folds and plaits, a rigging comprising tapes arranged in packs, means for supporting said rigging in said packs and means for releasing said parachute body and rigging from said supports on the application of the load. 10
- 15 2. In a parachute, the combination with a parachute body radially plaited and laid in concentric folds, of a launching disk for supporting said body normally in said symmetrical folds and plaits, a rigging comprising main and doublet tapes arranged in packs, means for supporting said rigging in said packs, and means whereby as the weight of the load is exerted said tapes will be first extended and the folds and plaits of the 20 25 parachute body successively released in ordered sequence from the periphery toward the center and means for freeing the said body from its support. 30
3. In a parachute the combination with a parachute body radially plaited and laid in concentric folds, of a launching disk for supporting said body normally in said symmetrical folds and plaits, a rigging comprising tapes arranged in packs, means for supporting said rigging in said packs, means for attaching said tapes to the peripheral fold of said parachute body, means whereby upon the application of the load said tapes will be first extended, then the weight of the 35 40 45 load exerted upon the peripheral fold of the parachute body, freeing said fold and successively the remaining folds and plaits of the said body in ordered sequence from the periphery to the center to inclose a column of air and means for automatically releasing said parachute body and load from the said launching disk. 4. A parachute and means for supporting
- same in symmetric folds and plaits, a rigging for said parachute composed of tapes 50 arranged in packs, a support for said rigging, a center piece detachably connected to said parachute supporting means, the ends of the aforesaid packs and the support therefor being secured to said center piece and an 55 envelop to inclose the parachute and associated parts. 5. A support for a parachute and means for retaining said parachute in symmetric folds or plaits thereon or therein, a support 60 for the rigging of said parachute and its trapeze or the like, means for connecting said rigging with said parachute and means for detachably connecting said supports substantially as described. 6. A launching apparatus for a parachute comprising a launching disk adapted to support the parachute body in symmetric folds or plaits, a center piece adapted to be detachably connected with said disk, a support 70 for the rigging of the parachute connected to said center piece and an airtight and waterproof envelop to inclose the parachute and its operative parts substantially as described. 75 7. In a parachute the provision of a rigging composed of main tapes and doublet tapes so lapped together as to form packs the main tape packs having means whereby when they are thrown into tension the unlapping thereof is accompanied by continuous friction and resistance while the doublet tape packs when thrown into tension are instantaneously released substantially as described. 8. In a parachute launching device a support for the parachute body and means for detachably connecting said parachute body thereto, a rigging composed of tapes arranged in packs, a two part envelop for inclosing said parachute body and launching device, one portion of said envelop forming a support for the packed rigging, and means for temporarily holding said rigging in position on said support. 85 90

EVERARD RICHARD CALTHROP.
